UNITED STATES PATENT OFFICE.

VALENTINE WIRICK, OF ROCHELLE, ILLINOIS, ASSIGNOR TO HIMSELF, AND
JOHN H. SUTPHEN, OF HURON, DAKOTA TERRITORY.

DRILLING-MACHINE.

SPECIFICATION forming part of Letters Patent No. 413,218, dated October 22, 1889.

Application filed December 8, 1888. Serial No. 293,026. (No model.)

To all whom it may concern:

Be it known that I, VALENTINE WIRICK, of Rochelle, in the county of Ogle and State of Illinois, have invented a new and Improved 5 Drilling-Machine, of which the following is a full, clear, and exact description.

The invention relates to that class of drilling-machines used for boring wells, &c.; and the object of the invention is to provide a new 10 and improved drilling-machine which is simple and durable in construction and very effective in operation.

The invention consists of certain parts and details and combinations of the same, as will 15 be fully described hereinafter, and then pointed out in the claims.

Reference is to be had to the accompanying drawings, forming a part of this specification, in which similar letters of reference indicate 20 corresponding parts in all the figures.

Figure 1 is a plan view of the improvement. Fig. 2 is a front side elevation of the same. Fig. 3 is a rear side elevation of the same. Fig. 4 is a sectional side elevation of the same 25 on the line $x-x$ of Fig. 1. Fig. 5 is a sectional end elevation of the same on the line $y-y$ of Fig. 1. Fig. 6 is a front side elevation of the drum-wheel with the tripping device in section. Fig. 7 is a rear sectional side elevation of the 30 same. Fig. 8 is a sectional side elevation of part of the same in a different position. Fig. 9 is a sectional side elevation of the drum-wheel. Fig. 10 is a sectional side elevation of the drum-stopping arms on the line $z-z$ of Fig. 5. Fig. 11 is a like view of the drum-brake on the line $w-w$ of Fig. 5. Fig. 12 is a plan view of a locking device for the tripping mechanism. Fig. 13 is an end elevation of 35 part of the mast and its guides, and Fig. 14 is a sectional plan view of the fly-wheel.

On a suitably-constructed frame A is mounted transversely the main driving-shaft B, connected in a suitable manner with the machinery for imparting a rotary motion to 45 the said driving-shaft. On the shaft B is held to slide a clutch B', supported on a bell-crank lever B², fulcrumed on the main frame A, and pivotally connected by the link B³ with the upright lever B⁴, fulcrumed on the front of 50 the main frame and provided with the notch B⁵, adapted to engage a pin B⁶, secured on the

main frame and serving to lock said lever B⁴ in place when the machine is to be stopped.

The teeth of the clutch B' are adapted to engage correspondingly-shaped teeth on a 55 sleeve C, mounted to rotate loosely on the main driving-shaft B and carrying a sprocket-wheel C', over which passes a sprocket-chain C², also passing over the drum-wheel D, mounted to rotate loosely on the shaft E, held 60 in suitable bearings on the main frame A. The sprocket-chain C² also passes over a guide-wheel C³ to prevent said chain from becoming disengaged from the wheels D and C'.

The wheel D is preferably made as illustrated in Fig. 9, being composed of the body part D', having in its rim recesses D², forming the projections D³, against one end of which rests a spring D⁴, placed in the recess D², and resting at its other end against a pin 70 or projection D⁵, formed on the inside of a ring D⁶, over which passes the sprocket-chain C², before mentioned. The pin D⁵ projects through the ring D⁶ to the outside, forming the points for engaging the links of the 75 sprocket-chain C². When the chain C² is set in motion from the main driving-shaft, it exerts a pull on the ring D⁶ in the direction of the arrow a', and consequently said ring D⁶, with its pins D⁵, exerts a pressure against 80 the springs D⁴, thus making the said wheel D yielding, for the purpose hereinafter more fully described.

On the shaft E is secured the drum F, on which is fastened one end of the rope G, supporting the drilling-tool G' at its other end. The rope G passes from the drum F upward over a pulley G², mounted to rotate at the upper end of the mast G³, secured between the vertical beams A' by the bolts G⁴ and G⁵, 90 passing through the said vertical beams A' and the mast G³. When the lower bolt G⁵ is removed, the mast G³ can be swung into a horizontal position on the bolt G⁴, so as to permit an easy transportation of the entire 95 machine. The rope G, soon after it leaves the drum F, passes through an aperture in the horizontal bar G⁶, secured to the main frame A. The rope G is also guided in a U-shaped arm G⁷, secured to the upper ends 100 of the beams A'.

On the shaft E is secured an arm H, pro-

jecting through a recess F' in one end of the drum F . The arm H is pressed against the shoulder formed by the recess F' by a spring H' , held in the drum F and resting at one end 5 against the projection F^2 , formed on the inside of the said drum. The other end of the said spring presses against the arm H . The latter is adapted to be engaged by one end of a tripping-pawl I , fulcrumed on the rear face 10 of the wheel D , and connected by a link I' with a spring I^2 , secured on the said face of the wheel D . The outer end of the pawl I is adapted to be engaged by a notch J' , formed in the arm J , secured on the shaft J^2 , mounted 15 to turn in the wheel D and extending transversely through the same. On the front end of the said shaft J^2 is secured a curved arm J^3 , against the under side of which presses a spring J^4 , secured to one side of the wheel D .

20 The curved arm J^3 is adapted to be engaged by a friction-roller K , secured on one end of an arm K' , fastened to a gear-wheel K^2 , mounted to rotate loosely on the shaft E . The gear-wheel K^2 meshes into a pinion K^3 , 25 fastened on a shaft K^4 , mounted to turn in a suitable bearing on the main frame A and carrying a crank-arm K^5 , for imparting a rotary motion to the said shaft K^4 . A pawl K^6 , fulcrumed on the main frame A opposite the 30 pinion K^3 , is adapted to engage the teeth of the gear-wheel K^2 , serving to lock the latter in place. By turning the crank-arm K^5 the gear-wheel K^2 is rotated, and the arm K' , by being fastened on the said gear-wheel, turns 35 with the same, and consequently its friction-roller K assumes a different position. As the friction-roller K operates on the arm J^3 of the tripping device, the position of the said friction-roller regulates the stroke of the drilling- 40 tool G' .

The arm J can be locked in position when disengaged from the pawl I by means of an arm L , secured on a shaft L' , mounted to swing in suitable bearings fastened on the 45 wheel D . The shaft L' is held in place by a spring L^2 , secured on the wheel D and pressing against the said shaft. On the latter is formed an arm L^3 , standing at right angles to the arm L and adapted to be engaged by an 50 arm L^4 , projecting from a lever L^5 , fulcrumed on the transverse beams of the main frame A . When the lever L^5 stands in an inclined position, its arm L^4 does not engage the arm L^3 of the shaft L' ; but when the said lever L^5 55 is swung into a vertical position and the arm L^3 is swung outward then the arm L passes over one end of the arm J and locks the latter in position until the wheel D , in its rotation, brings said arm L^3 into contact with the 60 arm L^4 , whereby the latter pushes said arm L^3 inward against the face of the wheel D , thereby throwing the arm L from over the free end of the arm J , and the latter can be again acted on by the curved arm J^3 , engaging the friction-roller K .

65 On the drum F is held the stop-arm N , provided with segmental straps N' , secured to a

semicircular strap N^2 by means of bolts N^3 . The latter serve to adjust the arm N to any desired position on the drum F , and also to 70 tighten the straps $N' N^2$ on the said drum. On the outer end of the stop-arm N is formed a hook N^4 , adapted to engage a pin O , formed on an arm O' , pivoted on a rod O^2 , mounted to slide horizontally in suitable bearings in 75 the main frame A . A pin O^3 , secured on the rod O^2 , prevents the downward motion of the arm O' , so that the latter can swing upward, but is prevented from swinging downward. On the reduced part of the rod O^2 is coiled a 80 spring O^4 , resting at one end against the frame A and at its other end against the shoulder formed by the reduced part. The spring O^4 serves to hold the rod O^2 in an outermost position, at the same time forming a 85 cushion for the stop-arm N to strike against. The outer end of the rod O^2 is provided with notches O^5 , adapted to be engaged by a pawl O^6 , pivoted on one of the beams A' , and serving to lock the rod O^2 in place whenever 90 desired.

A lever P is pivotally connected with the rod O^2 , and also, by a link P' , is connected with a brake-strap P^2 , fitting against the drum F and pivotally connected at its other 95 end with a rod P^4 , extending downward onto the base of the frame A and against one of the beams A' , so that the said rod P^4 is prevented from swinging. The rod P^4 is also pivotally connected by a link P^5 with the extreme lower end of the lever P , so that when the latter swings outward with the rod O^2 the link P' exerts a pull on the strap P^2 , so that the latter brakes the drum F .

On the outer end of the drum F is secured 105 a ratchet-wheel Q , with which engages a pawl Q' , fulcrumed on the main frame A and serving to prevent a return movement of the said drum F whenever desired. On the shaft E , next to the outer end of the drum F , is held 110 loosely a disk R , provided with an arm R' , carrying the pin R^2 , projecting inward and serving to limit the motion of the stop-arm N . The disk R is provided with a segmental slot R^3 , through which passes a bolt R^4 , on 115 the outer end of which screws a nut R^5 against the main frame A , so that the head of the bolt R^4 presses said disk R against the frame A , thereby locking the said disk in any desired position. When the nut R^5 is loosened, 120 the disk R can be shifted until the pin R^2 assumes a certain relative position in regard to the arm N . The nut R^5 is then screwed up, 125 as above described, so as to lock said disk in place, and so that the pin R^2 will prevent too great a movement of the arm N .

The operation is as follows: When the lever B^4 is disengaged from the pin B^6 , as illustrated in Fig. 2, the clutch B' engages by its teeth the corresponding teeth of the sleeve C , 130 so that when the shaft B is rotated said sleeve C receives a rotary motion and by the sprocket-wheel C' and chain C^2 imparts a corresponding motion to the wheel D in the

direction of the arrow a' . The rotary motion of the latter brings its pawl I at every revolution in contact with the arm H, secured on the shaft E, so that the said arm H is carried along against the tension of the spring H', thereby turning the drum F and winding up the rope G. The winding of the rope G raises the drilling-tool G'. The arm J locks the pawl I in position, as shown in Fig. 8, until the wheel D in one revolution brings the curved arm J³ under the friction-roller K, so that the latter, on the outward movement of the wheel D, presses said arm J³ inward, so that the arm J, with its hook J', is swung outward and the latter is disengaged from the pawl I. The weight of the drilling-tool G, as well as the force of the spring H', causes a return movement of the arm H past the pawl I, so that the drum F becomes free to rotate and the weight of the drilling-tool rotates the drum, and the said tool drops downward. When the arm H was moving forward in the direction of the arrow a' , as before described, it caused the stopping-arm N to swing in the same direction, and when the drum F is free to rotate, as above described, then the stopping-arm N swings in the inverse direction of the arrow a' with the drum until its hooked end N⁴ strikes forcibly against the pin O, which limits its swinging motion, and also the rotary motion of the drum F, whereby a further unwinding of the rope G is prevented and the drilling-tool G' has arrived at the end of its downward stroke. When the arm N strikes against the arm O, the rod O² moves outward against the tension of the spring O⁴, and at the same time the lever P is swung outward and by its link P' and the strap P² brakes the drum F.

When the operator desires to stop the downward stroke of the drilling-tool G', he throws the pawl Q' in contact with the ratchet-wheel Q, so that the stopping-arm N is free to make its forward movement in the direction of the arrow a' , as above described, but is prevented from making its return-stroke, as the said pawl Q' engages the ratchet-wheel Q.

When the operator desires to increase the stroke of the drilling-tool G', he disengages the pawl K⁶ from the gear-wheel K², and then turns the hand-wheel K⁵, so as to turn the shaft K⁴, which by its pinion K³ turns the said gear-wheel K² in the direction of the arrow a' , thereby moving the friction-roller K into a different position in the direction of the arrow a' . When the desired position is reached, the pawl K⁶ is again thrown in contact with the gear-wheel K², and when the wheel D is now rotated, as above described, the tripping of the pawl I takes place at longer intervals than before, so that the arm H travels a longer distance before the pawl I is disengaged, and consequently more of the rope G is wound. The pawl I is always moved to its former position by being connected by the link I' with the spring I². The arms J and J³ are always returned to their original

positions by the spring J⁴ acting on the under side of the arm J³. The arms J³ and J, being secured on the same shaft J², move simultaneously.

When the operator desires to stop the machine, he throws the lever B⁴ into the position shown in Fig. 2, so that the clutch B' is disengaged from the sleeve C, and the latter ceases its motion with the main driving-shaft B, which may continue its rotary motion. The shaft B is provided with a compensating fly-wheel of any approved construction.

Having thus described my invention, what I claim as new, and desire to secure by Letters Patent, is—

1. In a drilling-machine, the combination, with a shaft, a drum mounted to rotate loosely thereon, and a rope held on the said drum and supporting the drilling-tool, of an arm secured to the shaft and engaging the said drum, a tripping-pawl adapted to engage and disengage the said arm, a wheel having a rotary motion and carrying the said pawl, and a notched arm adapted to engage and disengage the said pawl and held on the said wheel, substantially as shown and described.

2. In a drilling-machine, the combination, with a shaft, a drum mounted to rotate loosely thereon, and a rope held on the said drum and supporting the drilling-tool, of an arm secured to the shaft and engaging the said drum, a tripping-pawl adapted to engage and disengage the said arm, a wheel having a rotary motion and carrying the said pawl, a notched arm adapted to engage and disengage the said pawl and held on the said wheel, and a spring secured on the said wheel and acting on the said tripping-pawl, substantially as shown and described.

3. In a drilling-machine, the combination, with a shaft, a drum mounted to rotate loosely thereon, and a rope held on the said drum and supporting the drilling-tool, of an arm engaging the said drum, a tripping-pawl adapted to engage and disengage the said arm, a wheel having a rotary motion and carrying the said pawl, a notched arm adapted to engage and disengage the said pawl and held on the said wheel, a curved arm secured on the shaft of the said notched arm, a friction-roller arm adapted to be locked in place and engaged by the said curved arm at every revolution of the said wheel, and a spring secured to the said wheel and pressing the said curved arm outwardly, substantially as shown and described.

4. In a drilling-machine, the combination, with a shaft, a drum mounted to rotate loosely thereon, and a rope held on the said drum and supporting the drilling-tool, of an arm engaging the said drum, a tripping-pawl adapted to engage and disengage the said arm, a wheel having a rotary motion and carrying the said pawl, a notched arm adapted to engage and disengage the said pawl and held on the said wheel, a curved arm secured on the shaft of the said notched arm, a fric-

tion-roller arm adapted to be locked in place and engaged by the said curved arm at every revolution of the said arm, and means, substantially as described, for shifting the position of the said friction-roller arm, as set forth.

5 5. In a drilling-machine, the combination, with an adjustable friction-roller arm, of a wheel having a rotary motion and carrying a tripping device operated by the said friction-roller arm, a shaft on which the said wheel is mounted, a rope-drum mounted to rotate loosely on the said shaft and carrying the drilling-tool, and a yielding arm secured to the said shaft and acting on the said drum and being engaged and disengaged by the said tripping device at every revolution of the said wheel, substantially as shown and described.

6 6. In a drilling-machine, the combination, with a friction-roller arm held adjustable, of a wheel having a rotary motion and carrying a tripping device operated by the said friction-roller arm, a shaft on which the said wheel is mounted, a rope-drum mounted to rotate loosely on the said shaft and carrying the drilling-tool, a yielding arm secured to the said shaft and acting on the said drum and being engaged and disengaged by the said tripping device at every revolution of the said wheel, a stopping-arm, secured on the said drum, and a yielding rod against which strikes the said stopping-arm after the drum is disengaged, substantially as shown and described.

35 7. In a drilling-machine, the combination, with a friction-roller arm held adjustable, of a wheel having a rotary motion and carrying a tripping device operated by the said friction-roller arm, a shaft on which the said wheel is mounted, a rope-drum loosely mounted on the said shaft and carrying the drilling-tool, a yielding arm secured to the said shaft and acting on the said drum and being engaged and disengaged by the said tripping device at every revolution of the said wheel, a stopping-arm secured on the said drum, a yielding rod against which strikes the said stopping-arm after the drum is disengaged, and a brake mechanism operated from the said yielding rod and acting on the said drum, substantially as shown and described.

8. In a drilling-machine, the combination, with a friction-roller arm held adjustable, of a wheel having a rotary motion and carrying a tripping device operated by the said friction-roller arm, a shaft on which the said wheel is mounted, a rope-drum loosely mounted on the said shaft and carrying the drilling-tool, a yielding arm secured to the said shaft and acting on the said drum and being engaged and disengaged by the said tripping device at every revolution of the said wheel, a stopping-arm secured on the said drum, a yielding rod against which strikes the said stopping-arm after the drum is disengaged, and an adjustable pin to limit

the forward movement of the said stopping-arm when the drilling-tools are lifted, substantially as shown and described.

70 9. In a drilling-machine, the combination, with a friction-roller arm held adjustable, of a wheel having a rotary motion and carrying a tripping device operated by the said friction-roller arm, a shaft on which the said wheel is mounted, a rope-drum loosely mounted on the said shaft and carrying the drilling-tool, a yielding arm secured to the said shaft and acting on the said drum and being engaged and disengaged by the said tripping device at every revolution of the said wheel, a stopping-arm secured on the said drum, a yielding rod against which strikes the said stopping-arm after the drum is disengaged, a brake mechanism operated from the said yielding rod and acting on the said drum, a ratchet-wheel secured on the said drum, and a pawl adapted to engage the said ratchet-wheel to prevent a return motion of the drum, substantially as shown and described.

90 10. In a drilling-machine, the combination, with a wheel having a rotary motion and carrying a tripping device provided with a curved arm, of a friction-roller under which passes the said curved arm, an arm carrying the said friction-roller, a gear-wheel held concentric with the said wheel and carrying the said arm, a pinion meshing into the said gear-wheel, a hand-wheel for turning the said pinion, and a pawl for locking the said gear-wheel in place, substantially as shown and described.

95 11. In a drilling-machine, the combination, with a wheel having a rotary motion and carrying a tripping device, of a shaft on which turns loosely the said wheel, a drum loosely mounted on the said shaft and provided at one end with a recess, and an arm secured to the said shaft and projecting through the recess in the said drum and being also engaged and disengaged by the said tripping device at every revolution of the said shaft, substantially as shown and described.

105 12. In a drilling-machine, the combination, with a wheel having a rotary motion and carrying a tripping device, of a shaft on which turns loosely the said wheel, a drum loosely mounted on the said shaft and provided at one end with a recess, an arm fulcrumed loosely on the said shaft and projecting through the recess in the said drum, being also engaged and disengaged by the said tripping device at every revolution of the said shaft, and a spring pressing against the said arm, substantially as shown and described.

110 13. In a drilling-machine, the combination, with a shaft, a drum, and a yielding arm for rotating the said drum mounted to rotate loosely thereon, of a tripping-pawl adapted to engage the said yielding arm, a spring acting on the said tripping-pawl, a yielding wheel mounted to rotate and carrying the said tripping-pawl, a notched arm held to swing

on the said wheel and adapted to engage and disengage the said tripping-pawl, and an arm held to swing on the said wheel and serving to lock the said notched arm in place when 5 disengaged from the said tripping-pawl, substantially as shown and described.

14. In a drilling-machine, the combination, with a shaft, a drum, and a yielding arm for rotating the said drum mounted to rotate loosely thereon, of a tripping-pawl adapted to engage the said yielding arm, a spring acting on the said tripping-pawl, a yielding wheel mounted to rotate and carrying the said tripping-pawl, a notched arm held to swing on the said wheel and adapted to engage and disengage the said tripping-pawl, an arm held to swing on the said wheel and serving to lock the said notched arm in place when disengaged from the said tripping-pawl, 20 and a lever mounted to swing and adapted to operate the said arm so as to unlock the latter and the said notched arm, substantially as shown and described.

15. In a drilling-machine, the combination, 25 with a shaft and a drum mounted to turn loosely thereon, of a stopping-arm secured on the said drum, and a yielding rod carrying a pin against which strikes the said stopping-arm, substantially as shown and described.

16. In a drilling-machine, the combination, 30 with a shaft and a drum mounted to turn loosely thereon, of a stopping-arm secured on the said drum, a yielding rod carrying a pin

against which strikes the said stopping-arm, a brake-lever pivotally connected with the 35 said yielding rod, and a brake-band connected with the said lever and acting on the said drum, substantially as shown and described.

17. In a drilling-machine, the combination, 40 with a shaft and a drum mounted to turn loosely thereon, of a stopping-arm secured on the said drum, a yielding rod carrying a pin against which strikes the said stopping-arm, a brake-lever pivotally connected with said 45 yielding rod, a brake-band connected with said lever and acting on the drum, and an arm carrying a link pivoted to the said brake-lever, the said rod being also connected by a second link with the said brake-band, substantially as shown and described.

18. In a drilling-machine, the combination, with a shaft, a drum mounted to turn loosely thereon, and a stopping-arm secured on the said drum, of a slotted disk held concentric 55 with the said drum, a pin projecting from the said disk and forming a stop for the said stopping-arm, and a bolt passing through the slot in the said disk and serving to lock the latter in place, substantially as shown and 60 described.

VALENTINE WIRICK.
